UNITED STATES PATENT OFFICE.

SAMUEL T. LOCKWOOD, OF CHICAGO, ILLINOIS, ASSIGNOR TO DAVIS J. WHITING, OF SAME PLACE.

MACHINE FOR TURNING BAGS.

SPECIFICATION forming part of Letters Patent No. 297,141, dated April 22, 1884.

Application filed March 8, 1883. (No model.)

To all whom it may concern:

Be it known that I, SAMUEL T. LOCKWOOD, of Chicago, in the county of Cook and State of Illinois, have invented certain new and useful 5 Improvements in Machines for Turning Bags, of which the following, in connection with the accompanying drawings, is a specification.

In the drawings, Figure 1 is a top or plan view of a bag-turning machine embodying my 10 invention, with the top or cover thereof removed. Fig. 2 is a side view of the same. Fig. 3 is a rear view thereof. Fig. 4 is a section in the plane of the line $x-x$ of Fig. 2, viewed in the direction indicated by the arrow 15 there shown. Fig. 5 is a detail, the same being a vertical cross-section of the upper portion of the machine, more fully showing the construction of the sliding carriage and its supports and guides. Fig. 6 is a detail, the 20 same being a plan view of the means employed for permitting the lateral adjustment and expansion of the bag turning or reversing arms. Fig. 7 is a detail, the same being a vertical section showing the means 25 employed for reciprocating the carriage. Fig. 8 is a section in the plane of the line $y-y$ of Fig. 7, viewed in the direction indicated by the arrow there shown; and Fig. 9 is a detail, the 30 same being a side view of a part of the reversing-gearing shown in Fig. 8, but viewed from the opposite side from which the same parts are viewed as shown in Fig. 8.

Like letters of reference indicate like parts.

A represents the stationary part or main 35 frame of the machine, upon the upper or horizontal bars of which I secure metallic strips or tracks A' A' as is clearly shown in Fig. 5.

B is a traveling or reciprocating frame or carriage resting freely on the strips A' A'. 40 A'' A'' are blocks or guides secured to the carriage B, and overlapping the outer sides of the strips A' A' and the main frame, as shown, thus enabling the frame B to be reciprocated on the way or track formed by the frame A and strips A' A' without danger of its leaving the said track.

B' is a rack rigidly secured to the carriage B.

C C are bag turning or reversing arms, and 45 h h are shouldered plates mounted freely on a cross rod or bar, h', forming a part of the frame or carriage B, the said rod or bar pass-

ing through the shoulders of the said plates. Set-screws i i pass through the plates h h and meet the rod or bar h', thereby admitting of the said plates being adjusted laterally on the 55 said rod. The plates h h are slotted, as shown at the dotted lines at h'' h'' in Fig. 6. The arms C C are pivoted to the plates h h, as shown at a, and j j are pins or studs passing from the said arms into the slots h'' h''. Springs 60 a' a' are attached to the plates h h, and rest against the arms C C, as shown. These arms C C are expandable laterally, their inclined portions a'' a'' striking thimbles a''' a''' as the said arms move forward and while they are in the 65 bag, thereby expanding the bag to its full width as it is presented to the stripping-rollers, hereinafter referred to.

D is the bag-holder. This holder consists in part of the horizontal fingers b b and b' b'. 70 The fingers b' b' are attached to a horizontal rod, b'', passing through the upper ends of vertically-arranged rods c c, adapted to move vertically in suitable boxes or guides.

d is a cross-bar connecting the lower portions 75 of the rods C C, and e e are spiral springs pressing downward on the said bar d. The fingers b b are connected to a horizontal rod, b'', supported by means of brackets e' e', attached to the frame A, as is plainly indicated 80 in Fig. 4.

E is a rocking cam supported by the frame A, and extending at one end beneath the bar d, which rests thereon.

F is a wheel or roller attached to the carriage B, and traveling on the cam E as the 85 said carriage is reciprocated.

G is a table or cover arranged over the carriage and carriage-way.

f f are arms or wires secured in the thimbles a'' a''', which are mounted on a shaft, f', and said fingers f f extend underneath the forward end of the table G.

H H are stripping-rollers, one rolling on the other, the upper one of the said rollers having spindles projecting into slots in the bearings of that roller, as indicated in Fig. 2, thereby permitting the said upper roller to rise and fall slightly, according to the thickness of the material passing between the said 95 rollers.

I is a fly arranged to receive the bags from

the rollers H H, and I' is a fly-table upon which the bags are deposited by the fly.

J is a buffer on the forward end of the rack B'.

5 J' is a stop to aid in stopping and starting the carriage B. The stop J' consists of a horizontal rod supported in suitable bearings attached to the frame A.

J'' is a spiral spring surrounding the rod J, and resting at one end against the frame A, and at the other against a shoulder, e'', on the said rod.

Both ends of the cam or lever E, I make alike, or substantially as shown at g, and I employ 15 a rear set of arms CC, in connection with bag-holders, strippers, and a fly similar to those above described, thus making the machine double-headed or double-acting; but, as the machine may be single-acting, I have here 20 shown only one set of working-parts, the other set, when employed, being a duplicate thereof.

The operation of this machine is as follows: I lay a number of bags, one upon the other, on the table G, the open ends of the bags being

25 toward the bag-holders b and b'. When the carriage B is at or near the rear end of its track, the roller F holds up the forward end

of the lever E, and the bar d, as it rests upon the forward end of the said lever, is thereby 30 held at such a height that the fingers b' b' are held near enough to the fingers b b to permit a bag to be placed about all of the said fingers with facility. I then place the mouth or open end of the bag about the said fingers. When 35 the carriage moves forward, the forward end of the lever E descends, and the bar d moves down with the descending end of the said lever, owing to the action of the springs e e. The fingers b' b' then descend as far as the bag

40 will permit, and the mouth of the bag is thus stretched about the bag-holding fingers tightly enough to prevent it from being accidentally removed. By this time the forward ends of the arms CC are in position to strike that part

45 of the bag which is between the upper and lower pairs of fingers, and the continued forward movement of the said arms reverses or turns the bag and presents its bottom to the rollers H H, which strip the bag from the said 50 arms and fingers. The bag then slides down over the fly and is laid upon the fly-table. This operation is repeated as the carriage moves back and forth.

While it is not absolutely essential that this 55 machine should in all respects be automatic, I deem it best to make provision for rendering it as nearly automatic as practicable; and to that end I intend to reciprocate the carriage B, rotate the rollers H H, and operate the fly 60 I mechanically, and to embody means employed for these purposes in the machine. I do not, however, here intend to claim any particular means for reciprocating the carriage B, rotating the rollers H H, and operating the 65 fly, as means adapted to those ends are already well known, and may be applied to the uses referred to in the said machine without ma-

terial structural alteration; but, having shown means for rendering the said machine automatic, I may briefly state that the large spur-wheel K is mounted rigidly on a shaft and engages the rack B', and that a belt-wheel, K', is mounted on another shaft and driven by a driving-belt in the usual manner.

Between the belt-wheel and the wheel K is 75 gearing for reversing the direction of rotation of the wheel K, all of which is more clearly shown in Figs. 7, 8, and 9 than elsewhere in the drawings, and in which figures K'' represents the shaft of the wheel K; K''', the shaft 80 of the wheel K'; L, a loose belt-wheel on the shaft K'''; L', a belt-wheel loosely mounted on the shaft K''' and having on its outer side the spurs or cogs L''.

M is a spur-wheel, rigidly attached to the 85 shaft K'' and engaging the wheel K.

N is the drive-belt.

O is a sliding shaft or rod, having thereon fingers N' N', one passing beyond one edge and the other passing beyond the other edge 90 of the drive-belt.

P is a bell-crank pivoted to a pin or stud, m, extending from the rod O, the said bell-crank being also pivoted at its angle to the frame A.

Q is a lever pivoted at its lower end to the axle or shaft of the wheel K.

Q' is a connecting-rod connecting the lever Q and the bell-crank P.

n is a stud or pin on the outer side of the 100 rack-bar B'. In practice there are two of these studs; but the machine as represented in Fig. 2 is broken away near one end, and the second stud n does not there appear. It should be located on the bar B', and at such 105 a distance from the stud shown that the two studs operating alternately during the reciprocation of the rack-bar on the lever Q, which projects up between them, will reverse the machine by shifting the position of that lever 110 sufficiently for that purpose.

R is a shaft, and R' and R'' are spur-wheels thereon. The wheel R' engages the cogs L'', and the wheel R'' engages the wheel K.

The driving-belt is driven by means of a 115 pulley, V, on a driving-shaft, V', and is shifted either to the wheel K' or to the wheel L', the rod O having a movement sufficient to carry the said belt from one of the said wheels to the other without permitting it to remain 120 on the loose belt-wheel longer than may be necessary to permit the belt to be shifted in the manner described, the said loose belt-wheel being employed only for the purpose of preventing the belt from being partly on the 125 wheels K' and L' at the same time. When the belt is on the wheel K' the wheel K will be rotated in one direction by reason of its engagement with the wheel M, which is on the same shaft with the wheel K', the latter 130 being rigid on its shaft. When the belt is shifted to the wheel L' the wheel K will be rotated in the opposite direction by reason of its engagement with the wheel R'', which is in

connection with the wheel L', through the medium of the shaft R, wheel R', and cogs L'', but not in gear with the wheel M, excepting through the medium of the wheel K. The belt is shifted automatically from one belt-wheel to the other, because the wheel K, when rotated, reciprocates the rack B', thus carrying the studs n n against the lever Q and shifting it, and thereby shifting the belt through the medium of the bell-crank and the sliding rod O. The lower wheel, H, I rotate by means of the drive-chain V'', passing over a sprocket, V''', on the shaft of the said wheel, and over a sprocket, V''', on the shaft V'.
 15 S is a cam rigidly applied to the shaft K'', and S' is a vibrating lever carrying a roller, S''. T is a cord connecting the upper end of the lever S to an arm, T', on the shaft or arbor of the fly I.
 20 U is a sliding-bar linked at one end to an arm on the shaft or arbor of the fly, and U' is a spring exerting itself on the bar U in such a direction as to throw the fly-fingers over toward the table I' when the cord T is slack.
 25 The cam S, which moves as the wheel K moves, strikes the roller S'', which then rolls outward on the convexity of the cam, thereby throwing the lever S back and raising the fly through the medium of the cord T. When the cam S and wheel K move in a direction reverse to that referred to, the roller S'' rolls back or inward on the convexity of the cam, which movement, excepting for the action of the spring U', would permit the cord T to become slack; 30 but the said spring prevents that slack and returns the fly to the fly-table.
 The fingers b' b' may descend by gravity.
 While I have shown and described herein the combination of an expandible bag-holder adapted to hold open the mouths of the bags, a reciprocating bag-turner, the tilting-lever made cam-shaped near both ends, and the traveling rollers, I do not seek herein to claim the same, since such combination forms the subject of a claim in my application for a patent for improvements in machines for turning bags, filed May 23, 1883, Serial No. 95,917.
 Having thus described my invention, what I claim as new, and desire to secure by Letters Patent, is—
 1. The combination of separable bag-holding fingers, the reciprocating bag-turners, and the rotary stripping-rollers, with means for supporting and operating the said fingers, for reciprocating the bag-turners, and for rotating the said rollers, for the purposes set forth.
 2. The combination of the bag-holding fingers b' b', means for supporting the said fingers, the reciprocating bag-turners C C, the tilting cam or lever E, and the traveler F, with means for operating the said bag-holding fingers b'

from said cam or lever, and for reciprocating the said bag-turners and traveler, for the purposes set forth.

3. The combination of the fixed fingers b b, 65 the movable fingers b' b', means for supporting the fingers b b, means for carrying the fingers b' b', and the springs e e, with the reciprocating bag-turners C C, the cam E, the traveler F, a supporting-frame, and means for operating the 70 said several parts in conjunction with each other, for the purposes set forth.

4. The combination of fingers b b', adapted and arranged to hold open the mouth of the bag, supports for said fingers, a bar, and rods 75 connecting the said bar with the supports of fingers b', with a reciprocating bag-turner, a tilting cam or lever for operating the said fingers b', and extending underneath the said bar, a traveler, F, for actuating the said cam, and 80 a table for supporting the bags, substantially as and for the purposes set forth.

5. The combination of the bag-supporter or table G, with the bag-holding fingers b b and b' b', arranged, substantially as shown and described, with relation to the supporter G, the reciprocating pivoted bag-turners C C, located underneath the supporter G, and arranged to pass between the separable fingers b b and b' b', the cam or lever E, means for supporting the 90 said fingers, and operating them from the cam or lever E, and means for operating the said bag-turners and cam, substantially as and for the purposes set forth.

6. The combination of the fixed fingers b b, 95 a support for the said fingers, the fingers b' b', the horizontal rod b'', the vertically-movable rods c c, the cross-bar d, and a support for rods connected with the fingers b' b', with the tilting cam or lever E, extending underneath 100 the cross-bar d, a reciprocating bag-turner, the traveler F, and means for reciprocating the said turner and traveler, substantially as and for the purposes set forth.

7. The combination, with the bag-turning 105 mechanism, of the stripping-rollers H H, means for rotating the said rollers, and a bag-supporter, G, arranged substantially as shown and described, for the purposes set forth.

8. The combination of the laterally-expansible and reciprocating arms C C, the separable fingers b b', the stripping-rollers H H, and the springs a' a', means for expanding the said arms, for supporting and separating the said fingers, and for rotating the said rollers, all 110 operating in connection with each other, and driving-gearing for reciprocating the said arms, for the purposes set forth.

SAMUEL T. LOCKWOOD.
